US0D1005346S

(12) **United States Design Patent** (10) **Patent No.:** **US D1,005,346 S**
(45) **Date of Patent:** **** Nov. 21, 2023**

(54) **WORK VEHICLE**

(71) Applicant: **Deere & Company**, Moline, IL (US)

(72) Inventors: **Daniel J. Huegerich**, Johnston, IA (US); **Felix Nagelin**, Malibu, CA (US); **Alex Kish**, Thousand Oaks, CA (US); **Ryan Pecinovsky**, Cedar Falls, IA (US); **Terry Zwart**, Loveland, CO (US); **Parker Wells**, Cedar Falls, IA (US); **Thomas Boe**, Cedar Falls, IA (US)

(73) Assignee: **DEERE & COMPANY**, Moline, IL (US)

(**) Term: **15 Years**

(21) Appl. No.: **29/868,136**

(22) Filed: **Nov. 21, 2022**

Related U.S. Application Data

(62) Division of application No. 29/709,227, filed on Oct. 11, 2019, now Pat. No. Des. 974,416.

(51) **LOC (14) Cl.** **12-09**

(52) **U.S. Cl.**

USPC **D15/23**

(57) **CLAIM**

The ornamental design for a work vehicle, as shown and described.

DESCRIPTION

FIG. 1 is a perspective view of a work vehicle according to our new design;

FIG. 2 is a first side elevational view thereof;

FIG. 3 is a second side elevational view thereof;

FIG. 4 is a first end elevational view thereof, shown enlarged for clarity;

FIG. 5 is a second end elevational view thereof shown enlarged for clarity;

FIG. 6 is a first plan view thereof; and,

FIG. 7 is a second plan view thereof.

The broken line representations in the figures depict unclaimed environment and form no part of the claimed design.

1 Claim, 7 Drawing Sheets
